UNITED STATES PATENT OFFICE.

JOHN HAYS HAMMOND, JR., OF GLOUCESTER, MASSACHUSETTS.

SMOKE-SCREEN PRODUCER.

Application filed December 30, 1916, Serial No. 139,902. Renewed February 20, 1922. Serial No. 538,095.

To all whom it may concern:

Be it known that I, JOHN HAYS HAMMOND, Jr., a citizen of the United States, and a resident of Gloucester, county of Essex, State of Massachusetts, have invented certain new and useful Improvements in Smoke-Screen Producers, of which the following is a specification.

Some of the objects of this invention are 10 to provide improved means for producing large volumes of dense smoke to serve as a screen for purposes of warfare; to provide an improved smoke screen producer which may be controlled in response to radiant 15 energy; to provide an improved method of producing a smoke screen; and to provide other improvements as will appear herein-after.

In the accompanying drawings Fig. 1 is 20 a perspective view showing smoke screen producers in operation; Fig. 2 a diagrammatic longitudinal central section on line 2—2 of Fig. 3 of a smoke screen producer constructed in accordance with this invention; Fig. 3 is a transverse section on line 25 3—3 of Fig. 2; Fig. 4 a fragmentary top plan view of a portion of the producer; Fig. 5 a diagrammatic side elevation of a modified form of a smoke screen producer 30 constructed in accordance with this invention; Fig. 6 a transverse section on line 6—6 of Fig. 5; Fig. 7 a fragmentary side elevation of a further modification of this invention; and Fig. 8 a transverse section on line 35 8—8 of Fig. 7.

Referring to the drawings, one embodiment of this invention comprises a smoke screen producer which includes an elongated airtight fire-box 10 having a bottom wall 11 and two substantially parallel side walls 12 extending upwardly from the bottom wall 11. The upper portions of the side walls 12 are turned inwardly and converge upwardly and are connected at their upper 40 edges by a substantially horizontal top wall 13 which is oblong and substantially rectangular in plan view. When this smoke screen producer is in operation the lower portion of the fire-box 10 is filled with pitch 45 or other suitable smoke making substance 14, which when sufficiently heated under conditions preventing complete combustion will produce large volumes of dense smoke. In Figs. 2 and 3 this pitch is shown as having 50 been liquified and as filling the fire-box to a depth indicated by the horizontal line 15.

For heating the pitch or other smoke producing substance 14 within the fire-box 10, the upper inclined portions of the two side walls 12 are provided respectively with two 60 series of main torches or Bunsen burners 25. These main torches 25 fit snugly in apertures provided therefor in the corresponding side walls and are inclined inwardly and downwardly in such a manner that the longitudinal axes of the main torches coincide with lines which intersect a common line extending longitudinally through the fire-box 10 arranged in a vertical plane extending centrally and longitudinally through the 70 fire-box. These main torches 25 are connected by branch pipes 26 to a main supply pipe 27 which is controlled by a valve 28 and which leads from a tank 29 containing gasoline or other suitable liquid fuel under 75 pneumatic pressure, or any suitable gaseous fuel under pressure, for supplying the main torches 25. The flow of fuel through each main torch 25 may be adjusted in a well known manner by means of a needle valve 80 30 with which each main torch 25 is provided.

For vaporizing the gasoline in the main torches 25, and for igniting the gasoline vapor as it flows into the fire-box from the 85 torches, each of the main torches 25 is provided with a relatively small auxiliary torch 35 which is arranged beneath the main torch 25 and which extends inwardly and upwardly through an opening provided therefor in the corresponding side wall of the fire-box 10. These auxiliary torches 35 are connected by branch pipes 36 to a main supply pipe 36 leading from the source 29 of liquid fuel and are kept constantly burning in order to maintain the inner ends of the main torches 25 at suitable temperatures and to ignite the gasoline vapor whenever it is permitted to be generated in the main torches. The inner end of each main torch 25 is preferably surrounded by a flat annular baffle plate 37 made of metal or other heat conducting material to facilitate the heating of the inner portions of the main torches 25 by the action of the flames of the auxiliary 95 torches 35, the auxiliary torches 35 being arranged to direct their flames upon these baffle plates 37 respectively.

For facilitating the partial combustion of the pitch or other smoke producing substance 14 in the fire-box, a shaft 40 extends longitudinally and horizontally through the fire-

box 10 in such a position as to be normally beneath the level of the pitch 14 or other combustible material. The ends of this shaft 40 extend snugly but rotatively through suitable bearings 41 provided therefor in the opposite ends of the fire-box 10, and the shaft 40 is arranged to be rotated by an electric motor 45 or other suitable motor which, in the form shown, acts through gears 46 and 47 to drive the shaft 40 through the intermediary of the friction clutch 48. The shaft 40 is provided with a plurality of rigid prongs 49 rigidly secured thereto and radiating therefrom. The shaft 40, with the prongs 49 carried thereby, begins to rotate only after the pitch or other substance 14 has been sufficiently softened by the action of the heat from the main torches 25. The motor 45 is arranged to be controlled in response to radiant energy, as hereinafter described, and after the motor has been energized the friction clutch 48 permits the motor to rotate without rotating the shaft 40 and the prongs 49 carried thereby until the pitch 14 has been sufficiently softened.

For discharging the smoke from the fire-box 10 any suitable smoke stack 55 is provided which communicates with the interior of the fire-box through any suitable opening 56 provided therefor in one end of the fire-box.

For regulating the amount of air which is permitted to enter the fire-box 10 the top wall 13 of the oven is provided with a plurality of openings 60, which are arranged to be controlled by a horizontal plate or damper 61 which is slidably mounted upon the upper surface of the top wall 13 of the fire-box, and which is slidably held between two cleats 62 secured to the top wall of the oven and overlapping the upper surface of the damper 61.

For controlling the operation of this improved smoke screen producer in response to radiant energy transmitted from a distant station, a receiving system for radiant energy is provided, comprising an antenna or open aerial circuit 74 which is carried by the boat or other movable body upon which the smoke producer is mounted, and which is grounded as at 75 in any suitable manner. This antenna 74 has in series therewith a coil 76 which is inductively connected to a secondary coil 77 which is in a closed oscillatory circuit including a variable condenser 78 and which is arranged to control a gaseous detector 79 or any other suitable detector. The detector 79 is arranged to control in a well known manner a circuit including a battery or other source of electrical energy 80 and a relay 81 which controls a normally open circuit including a battery or other source of electrical energy 82 and a solenoid 83.

The valve 28, which controls the flow of

combustible fluid to the main torches 25, includes and is controlled by a valve stem 84 upon which is loosely mounted a pinion 85 which engages a rack 87 which is carried by a piston rod 88 which is arranged to reciprocate through one end of a cylinder 89, and which has secured to its inner end a piston 90 which is normally pressed inwardly or towards the left, viewing Fig. 3, by a spiral spring 91 arranged within the cylinder 89 and surrounding the piston rod 88 between the piston 90 and the right hand end of the cylinder 89.

The cylinder 89 is arranged to receive compressed air through a pipe 95 which leads from a tank 96 or other suitable source of supply of compressed air. The air tank 96 is preferably arranged above the gasoline tank 29 and communicates with the gasoline tank through pipe 97 opening into the upper portion of the gasoline tank 29. The inlet of compressed air into the left hand end of the cylinder 89 from the pipe 95, and the outlet of compressed air from the left end of the cylinder 89 through an exhaust pipe 97 provided therefor, are controlled by a valve which is arranged to be reciprocated by a spring pressed core 98 which projects within the solenoid 83 and which is arranged to be actuated thereby.

Pivottally secured to the pinion 85 is a spring pressed pawl 100 which is arranged to actuate a ratchet 101 which is rigidly secured to the valve stem 84, and which in the form shown is provided with four teeth. The construction of the valve 28 and its actuating mechanism is such that each time an impulse of radiant energy is received by the antenna 74, the valve stem 84 will be rotated through a single step of ninety degrees, and when the valve stem 84 is in a given initial position or has been rotated through two steps or 180 degrees therefrom communication will be established between the tank 29 and the main torches 25, and when the valve stem is in either of its two other positions no gasoline will be permitted to flow from the tank 29 to the main torches 25.

For controlling the operation of the electric motor 45, a disc 110 of insulating material is rigidly secured to one end of the valve stem 84, and is provided with two diametrically opposed contact plates 111, and two brushes 112 and 113 are mounted upon any suitable fixed insulating support 114, and arranged to engage against the disc 110 and to engage simultaneously against one or the other of the contact plates 111 when the valve stem 84 is in either of its operative positions to permit the gasoline to flow from the tank 29 to the main burners 25. One of these brushes 112 is connected by a conductor 115 to one pole of a battery 116 or other source of electric energy, the other pole of which is connected by a conductor

117 to one pole of the motor 45. The other brush 112 is connected by a conductor 118 with the other pole of the motor 45. The arrangement is such that when the valve 28 5 is in either of its operative positions, the circuit will be closed through the brushes 112 and 113, corresponding contact plate 111, battery 116 and motor 45, thus energizing the motor, and when the valve 28 is in 10 either of its inoperative positions, the brushes 112 and 113 will rest upon the insulating disc 110, and the circuit through the brushes 112 and 113, battery 116 and motor 45 will be broken thus deenergizing the motor. By 15 this arrangement, the motor will be energized only when the main burners 25 are in operation.

In the operation of the improved smoke screen producer shown in Figs. 2 and 3, the 20 auxiliary torches 35 are kept continually burning, and the valve stem 84 is normally held in such a position by the rack 87 that no gasoline or other liquid fuel is permitted to pass from the tank 29 to the main torches 25 and the motor 45 will not be energized. Consequently, normally, the motor 45 and the main torches 25 are not in operation and no appreciable amount of smoke is produced within the fire-box 10. When, however, it 25 is desired to operate the smoke producer, the antenna 74 is energized by sending a suitable signal from the control station and this causes the operation of the detector 79 and the closing of the circuit through the battery 30 35 82 and solenoid 83, whereupon the valve of the cylinder 89 is operated to close the exhaust 97 and to admit compressed air from the tank 96 through the pipe 95, thus forcing the piston rod 88 outwardly and rotating the valve stem 84 into such a position 40 as to permit the gasoline or other liquid fuel to flow from the tank 29 through the pipe 27 and valve 28 and through the branch pipes 26 into the main torches 25, and to 45 close the circuit through the brushes 112 and 113 and motor 45. The main torches 25 are thus caused to operate and to direct their flames upon the pitch or other readily combustible material 14 within the fire-box 10, 50 thus melting the pitch and permitting the shaft 40, with its prongs 49, to rotate to facilitate a partial combustion of the pitch and to prevent the formation of a greasy scum upon the upper surface of the pitch. 55 The damper 61 is adjusted so as to prevent a complete combustion of the pitch, and thus to cause the production of a maximum volume of dense smoke.

When it is desired to cause the cessation 60 of the operation of the smoke screen producer, a second signal or impulse of radiant energy is caused to act upon the receiving antenna 74, and this acts through the detector 79, as hereinbefore described, to rotate the valve stem 84 through ninety de-

grees and into a neutral position in which the flow of gasoline from the tank 29 to the main burners 25 is stopped by the valve 28, and the circuit through the battery 116 and motor 45 is broken by the commutator 110, 70 thus rendering the device inoperative.

The modified form of this invention shown in Figs. 5 and 6, comprises a closed stationary fire-box 125, having at one end an outlet 126 through which the fire-box 75 communicates with the lower end of a stationary vertical delivery pipe 127, which has an open upper end through which the smoke is delivered into the atmosphere. For controlling the admission of air into the oven 80 125, the top wall of the fire-box is provided with a plurality of apertures 128 which are controlled by a damper 129 which is mounted to slide longitudinally of the fire-box in a fixed path, the damper 129 being provided 85 with suitable openings 129' arranged to co-operate with the openings 128 in the upper wall of the fire-box when the damper 129 is in a suitable position. Extending longitudinally of the fire-box 125 and outside 90 thereof, is a substantially horizontal rigid rod 130 which is arranged to rotate about a fixed axis coincident with its longitudinal axis in bearings 131 which are fixedly secured to the wall of the fire-box 125. Rigidly secured to the rod 130 are a plurality of gasoline burners 135 of any well known or suitable construction, which are arranged to extend through circular openings 136 provided therefor in the wall of the fire-box 100 125 and to project inwardly within the fire-box. The portion of each burner 135 which projects through the wall of the fire-box is provided with a spherical enlargement 137 which is coaxial with the rod 130 and which is arranged to completely close at all times the corresponding circular opening 136 through the wall of the fire-box. Adjacent the inner ends of the burners 135, the fire-box 125 is provided with a downwardly depending portion 140 which is filled with pitch 141 or other suitable smoke making substance which when sufficiently heated under conditions preventing complete combustion, will produce large volumes of dense 110 smoke.

For oscillating the burners 135 from an inoperative position (shown in full lines in Fig. 6,) into an operative position (shown in broken lines in Fig. 6), a crank arm 145 is 120 rigidly secured to one end of the shaft 130, and is pivotally secured at its free end to one end of a connecting rod 146, the other end of which is pivotally secured to a disc 147 which is rigidly secured to one end of a shaft 148, which is mounted in stationary bearing 149 to rotate about a fixed axis coincident with its longitudinal axis. Rigidly secured upon the shaft 148 is a ratchet 150 having two diametrically opposed teeth and which is ar- 125 130

41
ranged to be actuated by a spring pressed pawl 151 which is pivotally secured to a gear 152 which loosely surrounds the shaft 148. The gear 152 is engaged by a rack 155 which is rigidly secured to one end of a piston rod 156, the other end of which is provided with a piston 157 which is arranged to reciprocate in a fixed cylinder 158, the piston 157 being held in its innermost position 10 in the cylinder 158 by means of a spiral spring 159 surrounding the piston rod 156, and arranged within the cylinder 158. The cylinder 158 is provided with a valve casing 165, in which reciprocates a valve 166 which 15 controls the admission of compressed air into and the exhaust of compressed air from the inner end of the cylinder 158. The valve 166 is controlled by a solenoid 83 which is operatively connected, as hereinbefore described, to an antenna 74 in such a manner that the system may be controlled in response to radiant energy.

A stationary tank 170 of compressed air or other fluid under pressure is connected by 25 a pipe 171 to the valve casing 165 for supplying the cylinder 158 with fluid under pressure, the passage of air from the pipe 171 to the cylinder 158 being controlled by the valve 166. 30 For supplying the burners 135 with gasoline or other liquid fuel, a stationary tank 175 is provided, the upper portion of which is preferably connected by pipe 176 to the air tank 170, the gasoline tank 175 being in communication with the air tank 170 at all times through the pipe 176. The gasoline tank 175 is connected by a main pipe 177 and flexible branch pipes 178 with the three burners 135 respectively, and the gasoline 35 from the tank 175 is forced into the burners under the pressure of the air from the tank 170.

For increasing the amount of smoke produced by the burners 135, a plurality of spraying devices 180 are arranged in the upper portion of the fire-box 125, and in vertical alinement with the receptacle 140 for holding the pitch. These spraying devices 180 are connected by branch pipes 181 45 to a main pipe 182 which leads from a tank 183 or other source of supply of any well known or suitable liquid fire extinguishing means, such for instance, as "carbon tetrachloride" or 50 any other suitable fire extinguishing substance. The main pipe 182 is controlled by a vertically reciprocating valve 185 which is pivotally connected to one end of an eccentric rod 186, the other end of which 55 is provided with an eccentric yoke or strap 187 which surrounds an eccentric 188 which is rigidly secured upon the shaft 130, and is so arranged that when the shaft 130 is in an inoperative position, as shown in Fig. 6, the valve 185 will be

closed, but when the shaft 130 is in an operative position to direct the burners 135 downwardly, then the valve 185 will be open and will permit the fire extinguishing fluid to flow from the tank 183 into the spraying devices 180 by which the fluid will be sprayed over the surface of the pitch 141 or other smoke producing material.

In this modified form, the fire-box 125 may be provided, as hereinbefore described, with 75 a horizontal shaft 40 extending longitudinally therethrough, and having rigidly secured thereto a plurality of rigid prongs 49 arranged to agitate the pitch 141, the shaft 40 being driven through a friction clutch 48 by motor 45, as hereinbefore described. In this form of the invention, the motor 45 is arranged to be controlled by a commutator comprising an insulating disc 190 rigidly secured to the shaft 148, and provided with 80 a conducting segment 191 which is arranged to be engaged by two brushes 192 which are mounted upon a stationary insulating block 193. One of the brushes 192 is connected by a conductor 194 with one terminal of the 85 motor 45, and the other brush 192 is connected by a conductor 195 with one terminal of a battery 196, or other source of electric energy, the other terminal of which is connected by a conductor 197 with the 90 other terminal of the motor 45. The conducting segment 191 is so arranged that when the burners 135 are in an inoperative position, as shown in Figs. 5 and 6, the conducting segment 191 will be out of contact 95 with the brushes 192, but when the burners 135 are in their operative position, as shown on dotted lines in Fig. 6, the conducting segment 191 will be in contact with the brushes 192, and will close the circuit 100 through the battery 196 and the motor 45, and thus cause a rotation of the pinion 46, and a consequent rotation of the shaft 40 when the pitch 141 has been sufficiently softened, as hereinbefore described.

110 In the operation of the modified form of this invention shown in Figs. 5 and 6, the parts are normally in the positions shown in full lines in the drawings, and gasoline is being constantly forced into the burners 135 115 through the main pipe 177 and branch pipes 178, and the main burners 135 are constantly burning and normally directing their flames horizontally over the pitch 141, but when an impulse of radiant energy is received by 120 the antenna 74, the valve 165 will be operated to admit air from the pipe 171 into the inner end of the cylinder 158, and will force the piston 157 outwardly, thus causing the rack 155, to rotate the gear 152 through a 125 half a revolution, which will cause the connecting rod 146 to rock the crank arm 145, and the shaft 130 and burners 135 carried thereby, through an arc of approximately forty-five degrees to swing the burners 135 130

- into the operative position indicated in dotted lines in Fig. 6, to direct the flames upon the upper surface of the pitch 141. At the same time, the circuit will be closed by the 5 commutator 190, and brushes 192, through the battery 196 and motor 45, thus causing the rotation of the shaft 40 and the prongs 49, as soon as the pitch 141 has been sufficiently softened. At the same time that the 10 burners 135 are moved into operative position, the valve 185 will be opened by the action of the shaft 130 and eccentric 188, and will permit fire extinguishing fluid to flow through the pipe 182 and branch pipes 15 181, into the spraying devices 180 from which it will be sprayed over the surface of the pitch 141. The combined action of the burners 135 and the spraying devices 180, when the amount of air admitted to the fire- 20 box 125 is suitably regulated by the damper 129, will produce large volumes of dense smoke which will be permitted to exhaust through the smoke stack 127. When it is desired to stop the production of smoke, a 25 second signal of radiant energy is transmitted to the antenna, thus causing a second energization of the solenoid 83 and the consequent outward movement of the rack 155, whereupon the gear 152 will be rotated 30 through a half a revolution, and the connecting rod 146 will be thus returned to its initial position, as shown in Fig. 6, thus returning the burners 135 to their inoperative position and simultaneously closing the valve 35 185 to stop the flow of fire extinguishing fluid from the tank 183, and at the same time breaking the circuit through the brushes 192, battery 196 and motor 45, and thus stopping the rotation of the motor and 40 the shaft 40 and prongs 49 carried thereby, whereupon no appreciable amount of smoke will be produced in the fire-box 125.
- In the modified form of this invention shown in Figs. 7 and 8, the system comprises 45 a stationary fire-box 200 which is arranged to contain a predetermined amount of pitch 201 or other smoke producing material, and provided with a plurality of gasoline burners 205 extending snugly through one 50 of the vertical walls of the furnace, and held in fixed positions, the burners being inclined downwardly and inwardly, so as to project their flames over the upper surface of the pitch 201. The burners 205 are connected by branch pipes 206 to a main pipe 177 through which they are connected as hereinbefore described to the tank 175 containing gasoline under pressure from the air tank 170, as shown in Fig. 5.
- 60 For rendering the burners 205 operative or inoperative a substantially horizontal shaft 210 extends longitudinally through the oven 200, and is arranged to rotate about an axis coincident with the longitudinal axis of the shaft 210. Rigidly secured to one end of the
- shaft 210, is a crank arm 211, which is pivotally connected at its free end to a connecting rod 146 which corresponds to the connecting rod 146 shown in Figs. 5 and 6, and is arranged to be operated as hereinbefore 70 described, to oscillate the shaft 210 through about forty-five degrees whenever an impulse of radiant energy is received by the antenna 74, as hereinbefore described.
- Extending longitudinally within the fire- 75 box 200, is a flat baffle plate 215, which is rigidly connected to the shaft 210 by radial arms 216. The upper surface of the plate 215 is preferably covered by a comparatively thick layer 217 of asbestos or other heat insulating material, which is secured to the plate 215. The plate 215 is so arranged with respect to the shaft 210, that when the shaft 210 is in its inoperative position, as shown in full lines in Figs. 7 and 8, the plate 215 80 will be arranged horizontally in the path of the flames from the burners 205, and will protect the pitch 201 from the action of the burners, and when the shaft 210 has been oscillated through ninety degrees as a result 85 of the action of impulse of radiant energy, the plate 215 will be correspondingly rotated into the position shown in dotted lines in Fig. 8 where it will be out of the path of the flames from the burners 205 and will 90 permit the burners to act upon the pitch 201. The fire-box 200 is provided as hereinbefore described, with a plurality of spraying devices 180, which are connected by branch pipes 181, and a main pipe 182 to 100 the tank 183 containing a fire extinguishing liquid or fluid. The main pipe 182 is controlled as hereinbefore described, by a valve 185 which is actuated by a connecting rod 186 which is controlled by a yoke 187 which 105 surrounds an eccentric 188 which is fixed upon the shaft 210, the arrangement being such that when the baffle plate 215 is in its horizontal position, as shown in Fig. 8, the valve 185 will be closed and will prevent the 110 flow of fluid from the tank 183 to the spraying devices 180, and when the baffle plate 215 is in its vertical position, as shown in dotted lines in Fig. 8, the valve 185 will be 115 open and will permit fluid to flow from the tank 183 to the spraying devices 180.
- The fire-box 200 may also be provided, as hereinbefore described, with a horizontal shaft 40 upon which are rigidly secured a plurality of prongs 49, the shaft 40 being 120 arranged to be rotated as hereinbefore described, by a motor 45, which is controlled as hereinbefore described and shown in Fig. 5.
- In the operation of the modified form of 125 this invention shown in Figs. 7 and 8, the burners 205 are constantly operated, and normally no fire extinguishing fluid is permitted to flow from the tank 183 through the spraying devices 180. The baffle plate 215 130

is normally in the position shown in Fig. 8 to protect the pitch 201 from the action of the burners 205. When an impulse of radiant energy is received by the antenna 74, the connecting rod 146 is actuated, as hereinbefore described, to rotate the shaft 210 through about ninety degrees, and to swing the baffle plate 215 into its operative position and simultaneously to admit fire extinguishing fluid from the tank 183 to the spraying devices 180. At the same time, the motor 45 is energized, as hereinbefore described.

When it is desired to cause a cessation in the operation of the smoke screen producer, a second impulse or signal of radiant energy is transmitted to the receiving antenna 74, and this causes, as hereinbefore described, a rotation of the shaft 148 through half a revolution, which acts to rotate the shaft 210 through about ninety degrees to swing the plate 215 from an operative position into an inoperative position, as shown in full lines in Fig. 8. At the same time, the rotation of the shaft 210 acts to close the valve 185 to stop the flow of fire extinguishing fluid from the tank 183, and the rotation of the shaft 148 causes a corresponding rotation of the commutator 190 and the consequent breaking of the circuit through the battery 196 and motor 45, and the smoke producer is thus rendered inoperative.

Although only a few of the forms in which this invention may be embodied have been shown herein, it is to be understood that the invention is not restricted to any particular construction, but might be embodied in various forms without departing from the spirit of the invention or the scope of the appended claims.

Having thus fully described this invention, I claim and desire to protect by Letters Patent of the United States:

1. A smoke screen producer comprising a fire-box, a burner arranged to produce an imperfect combustion of smoke producing material in said fire-box, means for injecting fire retarding material in said fire-box, and means responsive to radiant energy for controlling said burner and said injecting means.

2. A smoke screen producer comprising a fire-box, a burner arranged to produce an imperfect combustion of smoke producing material in said fire-box, means for injecting fire extinguishing material into said fire-box, and means responsive to radiant energy for controlling said burner and said injecting means.

3. A smoke screen producer comprising a fire-box, means for producing an imperfect combustion of smoke producing material in said fire-box, and means for injecting fire retarding material into said fire-box.

4. A smoke screen producer comprising a

fire-box, means for producing a combustion of smoke producing material in said fire-box, means for injecting a fire retarding material into said fire-box, and means for simultaneously controlling said combustion means and said retarding material injecting means.

5. A smoke screen producer comprising means for holding smoke producing material, a burner operative to cause a combustion of said smoke producing material, means for injecting fire retarding material against said smoke producing material, controlling means operative to control said burner, and means governed by said controlling means for controlling said injection means.

6. A smoke screen producer, comprising means for containing smoke producing material, a burner for causing a combustion of said smoke producing material, means for controlling said burner, and means controlled by said controlling means for injecting fire retarding material against said smoke producing material.

7. A smoke screen producer, comprising means for containing smoke producing material, a burner for causing a combustion of said smoke producing material, means responsive to radiant energy for controlling said burner, and means controlled by said controlling means for injecting fire retarding material against said smoke producing material.

8. A smoke screen producer comprising a fire-box adapted to contain smoke producing material, means for admitting air into said fire-box, means for producing a partial combustion of said material in said fire-box, and means for injecting fire retarding material into said fire-box.

9. A smoke screen producer, comprising a fire-box adapted to contain smoke producing material, adjustable means for admitting air into said fire-box, means for producing a partial combustion of said material in said fire-box, and means for injecting fire retarding material into said fire-box.

10. A smoke screen producer comprising a fire-box adapted to contain smoke producing material, adjustable means for admitting air into said fire-box, a burner operative to cause a partial combustion of said smoke producing material, means for injecting fire retarding material into said fire-box, and controlling means operative to render said burner and said injecting means either simultaneously operative or simultaneously inoperative.

11. A smoke screen producer, comprising a fire-box adapted to contain smoke producing material, a burner arranged to act upon said material, means for agitating said material, controlling means operative to con-

- trol said burner, and means controlled by said controlling means for controlling said agitating means. 45
12. A smoke screen producer comprising a fire-box, means responsive to radiant energy for heating smoke producing material in said fire-box, and means for agitating said smoke producing means in said fire-box. 50
- 10 13. A smoke producer comprising a fire-box, means for heating smoke producing material in said fire-box, and means automatically operative to agitate said material in said fire-box. 55
- 15 14. A smoke producer comprising a fire-box, means for heating smoke producing material in said fire-box, means for agitating said material in said fire-box, actuating means, and a friction clutch connecting said 60 actuating means to said agitating means.
- 15 15. A smoke producer comprising a fire-box provided with an outlet, means for regulating the admission of air into said fire-box, means for heating smoke producing material in said fire-box, and means automatically operative to agitate said material in said fire-box. 65
- 30 16. A smoke producer comprising a fire-box, a main torch for heating smoke producing material in said fire-box, and means controlled by radiant energy for supplying said main torch with combustible fluid. 70
- 35 17. A smoke screen producer comprising a combustion chamber, means for burning smoke producing material therein and means for supplying a limited quantity of oxygen thereto, means for injecting fire extinguishing material and means responsive to radiant energy for controlling said 75 burning means and said injecting means. 80
- 40 18. A smoke screen producer comprising a combustion chamber, means for producing an imperfect combustion of smoke producing material therein, including means for
- limiting a supply of oxygen thereto and means for injecting fire retarding material into said chamber. 45
19. A smoke screen producer comprising a combustion chamber, means for producing an imperfect combustion of smoke producing material therein, including means for limiting a supply of oxygen thereto and means responsive to radiant energy for controlling said combustion means and said limiting means. 50
20. A smoke screen producer comprising means for holding smoke producing material, a burner operative to cause combustion of said material, means for conducting air in limited quantities thereto, means for injecting fire retarding material against said smoke producing material, controlling means operative to control said burner and means governed by said controlling means for controlling said injecting means. 55
21. A smoke screen producer comprising means for holding smoke producing material, a burner operative to cause combustion of said smoke producing material, means for supplying air in limited quantities thereto and means controlled by radiant energy for controlling combustion. 60
22. A smoke screen producer comprising a combustion chamber adapted to combine smoke producing material, adjustable means for admitting air in predetermined quantities into said chamber, means for controlling combustion of said material and means operated by radiant energy for actuating said means. 65

Signed at Gloucester, in the county of Essex and State of Mass., this 28th day of December, A. D. 1916.

JOHN HAYS HAMMOND, JR.
